UNITED STATES PATENT OFFICE.

WILLIAM F. LENNON, OF WILLIMANTIC, CONNECTICUT.

HEADLIGHT ATTACHMENT.

1,137,221.

Specification of Letters Patent. Patented Apr. 27, 1915.

Application filed February 12, 1915. Serial No. 7,668.

To all whom it may concern:

Be it known that I, WILLIAM FRANCIS LENNON, a citizen of the United States, residing at Willimantic, Windham county, 5 State of Connecticut, have invented certain new and useful Improvements in Headlight Attachments, of which the following is a full, clear, and exact description.

My invention relates to an improved 10 safety device for electric headlights for automobiles, the object being to provide a very simple, inexpensive and effective means for controlling the rays of light so as to prevent a glare in the eyes of any one approaching.

In the drawings: Figure 1 is a central longitudinal section of the reflector with an incandescent lamp in place with my deflector associated therewith in operative position. Fig. 2 is a perspective view of the deflector detached. Fig. 3 is a central sectional view of the deflector.

1 represents conventionally the usual headlight reflector.

25 2 represents the glass bulb of an electric incandescent lamp the same having a glass tip 3 and a plug 4.

5 represents the main body of a deflector or hood which is so shaped as to fit on to one 30 side of the bulb 2. The deflector or hood is constructed so that it is frictionally held in place by being engaged at its front edge with the glass tip 3 and at its rear edge with the rear part of the bulb adjacent to the

35 plug 4. The forward edge of the deflector is preferably provided with two slits forming between them a yielding spring clip 6 which is recessed or perforated to slip over the glass tip 3 to yieldingly engage the tip 35 or the bulb at the tip end. The rear edge of the deflector is preferably recessed to afford clearance for the plug 4. Those parts of the deflector on each side of this recess are so shaped as to embrace the lamp and

40 hold the rear edge of the deflector in place. These engaging parts on each side of said recess are preferably slightly extended to form integral spaced clips 7-7. I may, if desired, provide a yielding non-metallic pad 45 8 at the inside of the deflector to yieldingly

engage the tip 3 or the glass adjacent to said tip, thus reducing the danger of breakage to a minimum. It is well known that the glass used in bulbs of this sort is exceedingly thin and fragile and may be easily 55 broken. Since such devices as herein disclosed are subject to much vibration, a rigid engagement of the bulb at the tip 3 would invite breakage, but by my improved structure a non-rigid engagement is effected at 60 this point so that the danger of breakage is rendered practically negligible.

The pad 8 may be formed in any suitable way, for example, it may comprise a non-metallic eyelet which may be carried by the 65 spring clip 6 as shown.

The deflector may be adjusted to any desired position and may rest upon the top of, or be located under the bulb when the latter is in operative position. The particular location and adjustment of the deflector of course depends upon the particular design of the reflector 1. Since the engagement of the deflector with the glass bulb is a yielding one sufficient friction is afforded to hold 70 the deflector in any adjusted position. The interior of the body 5 may be brightened or "silvered" so as to direct the light rays, that would otherwise be cut off, against the reflector 1. 80

By slitting the deflector body it allows the body to expand somewhat so as to adapt itself to an oversized bulb.

What I claim is:

1. In a light deflector for an incandescent 85 lamp bulb, a main body portion designed to cover one side of the bulb, a spring clip at the forward edge of said deflector arranged to yieldingly engage the tip of the bulb with means at the rear edge of the deflector for 90 engaging the rear of the bulb, said last mentioned means comprising two spaced yielding clips integral with said main body.

2. In a deflector for an incandescent lamp bulb, a main body arranged to substantially 95 fit and cover one side of the lamp bulb, the forward edge of said body being slotted to form a spring clip, the latter being arranged to yieldingly engage the tip of the bulb, with means at the rear edge of said de- 100

flector to engage the rear of the bulb, said means and said spring clip serving to hold said deflector in place.

3. In a light deflector for an incandescent lamp bulb, a main body portion designed to cover one side of the bulb, a spring clip at the forward edge of said deflector arranged to yieldingly engage the tip of the bulb with means at the rear edge of the deflector for

engaging the rear of the bulb, said last mentioned means comprising two spaced flexible clips, and a non-metallic pad interposed between said spring clip and said bulb. ¹⁰
